[57] CLAIM

The ornamental design for a combined vacuum cleaner
hose and rack, as shown and described.

DESCRIPTION

FIG. 1 is a top, front and left side perspective view of a
combined vacuum cleaner hose and rack showing my
new design;

FIG. 2 is an enlarged left side elevational view thereof;
FIG. 3 is an enlarged right side elevational view
thereof;

FIG. 4 is an enlarged front elevational view thereof;
FIG. 5 is an enlarged rear elevational view thereof;
FIG. 6 is an enlarged top plan view thereof;
FIG. 7 is an enlarged bottom plan view thereof, and,
FIG. 8 is an enlarged left side elevational view thereof,
mounted to a vacuum cleaner upper portion which is
shown in broken lines.

The parts shown in broken lines in FIGS. 1-8 are shown
for illustrative purposes only and form no part of the
claimed design.
